Primary Examiner — Clint A Samuel(74) *Attorney, Agent, or Firm* — Rabin & Berdo, P.C.(57) **CLAIM**

The ornamental design for a lampshade as shown and described.

DESCRIPTION

1. Lampshade

FIG. 1 is a perspective view of a lampshade showing my new design;

FIG. 2 is a front view thereof;

FIG. 3 is a rear view thereof;

FIG. 4 is a top view thereof;

FIG. 5 is a bottom view thereof;

FIG. 6 is a left side view thereof; and

FIG. 7 is a right side view thereof.

Materials are made of glass and synthetic resin; this design embodies the appearance of a flat snowman; it is installed by being connected to the ceiling through a wire.

1 Claim, 7 Drawing Sheets(56)
